UNITED STATES PATENT OFFICE.

ARTHUR BENNETT, OF RAQUETTE LAKE, NEW YORK.

WATER-SCOOP FOR LOCOMOTIVE-TENDERS.

No. 901,315.

Specification of Letters Patent.

Patented Oct. 20, 1908.

Application filed May 26, 1908. Serial No. 435,064.

To all whom it may concern:

Be it known that I, ARTHUR BENNETT, a citizen of the United States, residing at Raquette Lake, in the county of Hamilton and State of New York, have invented new and useful Improvements in Water-Scoops for Locomotive-Tenders, of which the following is a specification.

This invention relates to apparatus where-
10 by locomotive tenders can be supplied with
water from troughs arranged along the rail-
road without stopping the train, and it re-
lates more particularly to a water scoop de-
signed for use in connection with elevated
15 troughs.

The invention has for one of its objects to
improve and simplify the construction and
operation of apparatus of this character so
as to be comparatively easy and inexpensive
20 to manufacture and install, thoroughly re-
liable and efficient in use, and readily ma-
nipulated.

Another object of the invention is the pro-
vision of a locomotive tender having a duct
25 mounted to swing outwardly from one side
of the tender into coöperative relation with
an elevated water trough for enabling the
scoop of the duct to automatically enter the
30 trough to take up water therefrom, the duct
being projected to operative position and re-
stored to normal position by means operated
by the fireman.

A further object of the invention is to pro-
vide means at the ends of the trough where-
35 by the scoop can freely enter and leave the
trough without attention on the part of the
fireman or operator.

With these objects in view and others, as
will appear as the description proceeds, the
40 invention comprises the various novel fea-
tures of construction and arrangement of
parts which will be more fully described
hereinafter and set forth with particularity
in the claims appended hereto.

45 In the accompanying drawings, which
illustrate one of the embodiments of the in-
vention, Figure 1 is a side view of a loco-
motive tender and water trough showing the
scoop in operative position therein, portions
50 being broken away to illustrate details of
construction. Fig. 2 is a transverse section
on line 2—2, Fig. 1. Fig. 3 is a plan view
of the rear portion of the tender and one ex-
tremity of the water trough. Fig. 4 is a lon-
55 gitudinal section of one extremity of the wa-

ter trough. Fig. 5 is a detailed sectional
view of the water scoop.

Similar reference characters are employed
to designate corresponding parts through-
out the views.

Referring to the drawing, A designates a
locomotive tender for the locomotive B, the
tender being of any approved construction
and having a coal-receiving compartment 1
and a water-carrying compartment 2. In 65
the top of the water compartment 2 is a
rectangular opening 3 through which the
water is supplied by the duct C. This duct
is attached at one end to the side of the
tender by hinges 4 so as to swing in a plane 70
transverse to the tender from its normal po-
sition closing the opening 2 to the operative
position with respect to the water-carrying
trough D. When the duct C is in closed
75 position as shown by dotted lines, Fig. 2,
its free end rests on a bracket or stop 5, and
when the duct is in open position, it rests on
the bottom of the recess 6 provided in the
top of the tender. In the front wall of the
80 duct is an inlet opening 7 in which is 80
hingedly mounted, at 8 Fig. 5, a for-
wardly extending scoop 9 that is adapted
to enter the trough and direct the water into
the opening 5 as the locomotive is in motion,
the inner end of the duct being open so that 85
the water can pass into the tender through
the opening 3.

The trough D is elevated to a suitable
height and mounted on posts 10 and dis-
posed parallel with the track over which the 90
locomotive is passing. This trough is
formed with a jacket 11 in which are steam or
other heating pipes 12 whereby the water in
the trough can be heated in winter, so as to
prevent freezing of the water. At the ends 95
of the trough are inclined guides 13 whereby
the chute 9 can smoothly enter and leave the
trough, and the extremities of the trough
have outwardly and downwardly inclined
surfaces 14 forming deflectors on which the 100
scoop 9 rides in entering and leaving the
trough, the deflectors terminating at a suit-
ably low point to insure the engagement of
the free edge of the scoop therewith as the
locomotive approaches the trough.

105 The duct or water scooping device C is
projected and retracted by the engineer, fire-
man, or other attendant, and for this pur-
pose an operating lever 15 is mounted in
the cab of the locomotive or at any other 110

suitable point, and connected with this lever are two cables or flexible elements 16 that ride over pulleys 17 on the tender and are connected with the device C. The elements 5 are connected with the lever 15 at points 18 and 19 located at opposite sides of the fulcrum 20 so that movement of the lever in one direction will project the water-scooping device to the full line position, Fig. 2, while movement in the opposite direction will 10 retract the device to the dotted line or normal position.

With an apparatus of this character, the tender can be easily and quickly replenished 15 while the train is going at a high rate of speed, and the water scooping device freely enters and leaves the trough without perceptible shock.

From the foregoing description, taken in 20 connection with the accompanying drawings, the advantages of the construction and of the method of operation will be readily apparent to those skilled in the art to which the invention appertains, and while I have 25 described the principle of operation of the invention, together with the device which I now consider to be the best embodiment thereof, I desire to have it understood that the device shown is merely illustrative, and 30 that such changes may be made when desired as are within the scope of the claims appended hereto.

Having thus described the invention, what 35 I claim is:—

1. The combination of a water trough elevated above and at one side of a track, with a locomotive tender, a water scooping device mounted on the tender, and means for projecting the device into coöperative relation 40 with the trough and for retracting said device.

2. The combination of a locomotive tender

having an opening, a water scooping device normally closing the opening, and means for projecting the device from the side of the 45 tender.

3. The combination of a locomotive tender, a water scooping device hingedly mounted on the tender to be projected from one side thereof, and means for projecting and 50 retracting the said device.

4. The combination of a locomotive tender having an opening and a recess adjacent the opening, a water scooping device disposed in the recess when in projected position and arranged to discharge water into 55 the opening, and means for projecting and retracting the device.

5. The combination of a tender, a duct hingedly mounted at one side thereof and 60 adapted to swing in a plane transverse to the direction of travel, said duct having an opening in its front, and a scoop carried on the outer end of the duct and arranged to conduct water into the opening, with a water 65 trough mounted above and at one side of the track on which the tender travels and into which the scoop is adapted to run.

6. The combination of a locomotive tender, a water scooping device adapted to be 70 projected laterally therefrom, separate flexible elements connected with the device, guiding means on the tender for the elements, and a lever connected with both elements and arranged to move the same simultaneously in opposite directions for projecting or retracting the said device.

In testimony whereof I affix my signature in presence of two witnesses.

ARTHUR BENNETT.
